METAL TRACTION DRIVE WHEEL

James M. Roberts, St. Joseph, Mo.

Application September 22, 1932
Serial No. 634,360

4 Claims. (Cl. 301—46)

My invention relates to a traction drive wheel and has as its main object the construction of a traction wheel provided with caulks so arranged that in soft ground excellent traction will be obtained while on hard ground and paved roads digging up and destruction of such ground and roads will be avoided.

Another object of my invention is the construction of a traction drive wheel in which traction 10 shoes having caulks are pivoted to the wheel, and each shoe is provided with a spring to resist resiliently the oscillations of the shoe.

Another object of my invention is to connect the shoes in groups by coupling bars so that the 15 rocking resistance of all the shoe springs of a group are effective on each shoe of the group as the shoe comes in contact with the ground during operation of the wheel.

Another object of my invention is the provision 20 of means manually to adjust and lock resiliently the shoes of a group in any desired position.

Still another object of my invention is the provision of a traction drive wheel which will operate more efficiently and more economically than 25 ordinary traction wheels.

I attain the objects of my invention by the mechanism illustrated in the accompanying drawings in which:

Fig. 1 is a view of my traction wheel in side 30 elevation, parts being shown in section, and other parts being omitted.

Fig. 2 is a vertical sectional view taken on the line X—X of Fig. 1.

Fig. 3 is an inner plan view of a traction shoe. 35

Fig. 4 is a side elevational view of a traction shoe.

Fig. 5 is a fragmentary side elevational view 40 of a certain type of shoe, one shoe of this type being employed in each group of shoes.

Fig. 6 is an end view, partly in section, of the shoe shown in Fig. 5.

Fig. 7 is a top plan view and

Fig. 8 is a view in side elevation of a coupling bar.

Fig. 9 is an inner plan view, partly in section, 45 of a fragment of the wheel rim showing a plurality of shoes mounted between two angle iron rim members.

Fig. 10 is a view in side elevation of the structure shown in Fig. 9.

Fig. 11 is an inner plan view, partly in section, showing a single shoe in its operative relation to a leaf spring secured to an angle iron rim member.

Fig. 12 is a view in side elevation of the structure shown in Fig. 11.

With continued reference to the drawings in which like numerals designate like parts, my traction wheel comprises the following structure: A wheel hub is provided and at each of the opposite ends thereof is a radially extending flange or disc 60 3. To each disc 3 the inner ends of spokes 2 of a series are secured and the outer ends of the spokes 2 of each series are secured to an angle iron rim member. In other words, two axially spaced angle iron rim members 1 are provided. 65 Shouldered bolts 6 connect the two rim members 1 and hold them in axially spaced relation, the bolts passing through the vertical flanges of the angle iron rim members. Radially inwardly of each shouldered bolt and in radial alignment 70 therewith a flange 23 is provided. Each flange 23 extends axially towards the median plane of the wheel and is integral with the vertical flange of an angle iron rim member. Half of the flanges 23 are on one rim member and half are on the 75 other rim member.

A plurality of traction shoes 4 substantially fills the space between the axially spaced rim members 1. Each shoe is pivotally mounted intermediate its ends on a shouldered bolt 6 and 80 has the sole or outer ground engaging surface of its main body portion curved on the same radius as the angle iron rim members. The outer surface of the main body portion of each shoe is normally flush with the radially outer surfaces 85 of the angle iron rim members. Each shoe has at each of its opposite ends a caulk 30 which extends in a general radial direction with respect to the wheel radially outwardly and inwardly of the periphery of the wheel, the radially outer portion of each caulk being curved away from the main body position of its shoe. A flat leaf spring 18 for each shoe is secured to a lug 23 by a bolt 38 and extends in such a manner as to constitute substantially a chord of the circle 90 which defines the periphery of the wheel rim. Each end of each leaf spring rests upon the inner end 31 of a caulk 30. Thus pivotal movement of the shoes on the bolts 6 is resiliently resisted.

The bolts 6 are shouldered as shown at 37 and have their ends threaded as at 36 to receive nuts.

It is to be noted that the width of the end portions of each shoe 4 is equal to substantially half the distance between the spaced rim members 1, 105 and that a trunnion-like portion 26 projects laterally from the longitudinal center of the shoe, making the central portion 26 which receives the bolt 6 of substantially the same width as the space between the rim members 1. The shoes 110

are arranged rights and lefts in two series, the 5 shoes of one series having their main body portions located to one side of the median plane of the wheel and the shoes of the other series having their main body portions located to the opposite side of the median plane of the wheel. The ends of the shoes of one series overlap the ends of the shoes of the other series. The portion 10 26 has a nave-like portion 28 provided with an aperture 29, for a bolt 6.

In the structure so far described, the shoes 15 may function individually. Under some conditions, however, it is desirable to control the operation of the shoes in groups. Accordingly, means are provided for connecting the shoes in 20 separate groups (three groups being shown in Fig. 1), and adjusting the positions of the shoes resiliently. In this arrangement, movement of any shoe is transmitted to all other shoes of the group and oscillations of the shoes are resiliently resisted. The shoes of each group are connected and adjusted as follows:

Extending radially inwardly of the wheel from 25 the central portion of each shoe is a leg 27. The leg 27' of one shoe of each group is longer than the legs of the other shoes and has at its inner end a transverse aperture 33. The leg 27 of each shoe has adjacent its inner end laterally projecting trunnion bars 24 having diametrical apertures 30 25. Coupling links 7 are provided. As shown clearly in Figs. 7 and 8, each coupling link has at each of its ends a transverse aperture 34 adapted to receive one end of a trunnion bar 24. Adjacent each aperture 34 a hook member 35 is 35 pivotally mounted on the coupling link, and the bill of the hook is adapted to enter an aperture 25 of a trunnion bar 24. The shoes 4 are connected by the coupling links 7 as clearly shown in Figs. 1, 9, and 10.

The shoes of each group may be resiliently 40 adjusted manually by the following means: A tube 12 has threaded onto its outer end a clevis cap 16 which carries a pair of apertured ears, the apertures receiving a pin 17 which also passes through the aperture 33 of the long leg 27' carried by one 45 shoe of the group, thus pivotally connecting the outer end of the tube to the shoe. A centrally perforated cap 14 is threaded onto the inner end of the tube 12. A pair of links 19 is positioned 50 between and secured to a pair of axially spaced spokes by spacing sleeves 20 and bolts 21 as most clearly shown in Fig. 2. Pivotally mounted between the links or bars 19 is a block 10 having a threaded aperture which receives the threaded inner end 11 of a rod 13 having fixed to it a handle 9. The rod passes slidably through the aperture in the cap 14 and ends within the tube 12 about centrally of the length of said tube. A button 22 is fixed to the outer end of the rod 13, 55 and contacting each side of the button is a compression spring 15 positioned within the tube 12. When the handle 9 is rotated in one direction, 60 the rod is threaded through the block 10 and slid through the cap 14 so that the button 22 compresses one of the springs 15. Thus the shoes of a group are resiliently urged to pivot in one direction 65 on their pivots 6. Rotation of the handle 9 in the opposite direction causes the shoes of the group to be resiliently urged to move in the opposite direction on their pivots.

The coupling bars and means to adjust resiliently the shoes in groups are used only under abnormal or adverse conditions of ground. First, the use of the coupling bars alone to connect the shoes in groups has the effect of adding

the rocking resistance of several shoe springs to that of any shoe of the group in contact with the ground. Second, where even greater tractive effort is required, the use of the resilient shoe adjusting means, including the springs 15, adds the 80 resistance of a spring 15 to the resistance of the springs 18. By use of the adjusting means, the shoes of any or all groups may be turned on their pivots so that their caulk will bite into ice or slick surfaces and afford increased traction.

Without the use of the coupling bars 7 and the means for resiliently adjusting the shoes in groups, my traction wheel will run over good roads and hard surfaces without digging up such roads or surfaces. The same thing is true where the coupling bars and resilient adjusting means are used if the shoes are so adjusted that the feet 85 27 extend radially of the wheel. However, the caulk will bite into soft ground, due to the force rotating the wheel and the force of the springs 18 to provide efficient traction.

When use of the means to adjust the shoes in groups is not desired, the clevis cap 16 of each adjusting device is detached from the long shoe leg 27' by removal of the pin 17 and this cap is 90 then detachably connected by pin 17 to a lug 3 secured to a spoke.

When it is not desired to use the coupling bars 7, they may be detached from the shoes, by manipulating the hooks 35, and stored in a box on 105 the tractor to which the wheel belongs.

The structure shown and described is particularly simple, practical, and efficient, but it is obvious that various changes may be made within the scope of the appended claims without departing 110 from the spirit of the invention.

I claim:

1. A tractor wheel comprising two axially spaced series of spokes, a pair of angle iron rim members secured to the outer ends of the spokes, 115 shouldered bolts connecting the rim members and holding them in axially spaced parallel relation, a plurality of circumferentially extending rockable shoes positioned between the rim members and each pivotally mounted intermediate its ends on a shouldered bolt, the end portions of each shoe being substantially one half the width and the central portion being of substantially the same width as the space between said rim members, and radially extending caulk at the ends 120 of the shoes, the shoes being arranged in rights and lefts with their ends overlapping each other, thus forming two rows of staggered caulk.

2. A traction wheel comprising two axially spaced series of spokes, a hub having a spoke disc 130 at each of its ends, two angle iron rim members, the inner ends of the spokes of each series being secured to a spoke disc and the outer ends thereof being secured to an angle iron rim member, shouldered bolts connecting the rim members and holding them in axially spaced parallel relation, 135 a plurality of circumferentially overlapping rockable shoes positioned between the rim members and each pivotally mounted intermediate its ends on a shouldered bolt, each shoe having its outer sole surface curved to correspond with the outer surface of the angle iron rim members and normally flush therewith, radially outwardly and inwardly extending caulk at the opposite ends of each shoe, lugs integral with the inner portions 140 of the rim members radially inwardly of and in alignment with the shouldered bolts, and a leaf spring for each shoe secured centrally to one of said lugs and having its ends resting on the inner ends of the shoe caulk to offer elastic resistance 145 150

- to rocking of the shoe during operation of the wheel.
3. A traction wheel comprising two axially spaced series of spokes, a hub having a spoke disc at each of its ends, two angle iron rim members, the inner ends of the spokes of each series being secured to a spoke disc and the outer ends thereof being secured to an angle iron rim member, shouldered bolts connecting the rim members and holding them in axially spaced parallel relation, a plurality of circumferentially overlapping rockable shoes positioned between the rims and each pivotally mounted intermediate its ends on a shouldered bolt, each shoe having its outer sole surface curved to correspond with the outer surface of the angle iron rim members and normally flush therewith, a caulk at each end of each shoe extending radially outwardly and inwardly of the wheel, a leg intermediate the ends of each shoe extending radially inwardly, coupling bars connecting the shoes in groups, one shoe of each group having a leg longer than that of the other shoes of the group, each leg having adjacent its inner end laterally extending diametrically apertured trunnions, each coupling bar having at each end an aperture receiving a trunnion and a pivoted hook received by a diametrical aperture in the trunnion, connection of the shoes in groups having the effect of making the resistance of each shoe to rocking as it contacts the ground the combined resistance of all of the shoes of a group to rocking movement.
4. A traction wheel comprising two axially spaced series of spokes, a pair of angle iron rim members connected to the outer ends of the spokes, shouldered bolts connecting the rim members and holding them in axially spaced parallel relation, a plurality of circumferentially extending overlapping rockable shoes positioned between the rim members and each pivotally mounted intermediate its ends on a shouldered bolt, each shoe having its outer surface curved to correspond to the curvature of the outer surface of the rim members and normally flush therewith, a caulk at each end of each shoe extending radially outwardly and inwardly of the wheel, a leg intermediate the ends of each shoe extending radially inwardly, coupling bars connecting the shoes in groups, one shoe of each group having a leg longer than that of the other shoes of the group, each leg having adjacent its inner end laterally extending diametrically apertured trunnions, each coupling bar having at each end an aperture receiving a trunnion and a pivoted hook received by a diametrical aperture in the trunnion, and a resilient adjusting device for each group of shoes, said adjusting device being pivotally connected adjacent one of its ends to a pair of axially spaced spokes and detachably and pivotally connected at its other end to the inner end of the longer leg of the group of shoes, whereby the shoes may be adjusted in groups and rocking of the shoes resiliently resisted.
